Primary Examiner — Elizabeth A. Albert(74) *Attorney, Agent, or Firm* — Birch, Stewart, Kolasch & Birch, LLP(57) **CLAIM**

The ornamental design for a pod for plant cultivator, as shown and described.

DESCRIPTION

FIG. 1 is a top perspective view of a pod for plant cultivator showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a bottom perspective view thereof;

FIG. 8 is also a perspective view thereof;

FIG. 9 is another perspective view thereof; and,

FIG. 10 is an exploded perspective view thereof.

The broken lines are included to show portions of the pod for plant cultivator and the plant cultivator that form no part of the claimed design.

1 Claim, 10 Drawing Sheets(56)
